(57) **CLAIM**

I claim the ornamental design for a bathroom mirror clock, as shown and described.

DESCRIPTION

FIG. 1 is a front view of the bathroom mirror clock.

FIG. 2 is a back view of the claimed design.

FIG. 3 is a left view of the claimed design.

FIG. 4 is a right view of the claimed design.

FIG. 5 is a top view of the claimed design.

FIG. 6 is a bottom view of the claimed design; and,

FIG. 7 is a perspective view of the claimed design.

The broken lines in FIG. 2 depict portions of the bathroom mirror clock that form no part of the claimed design.
